(57) **CLAIM**

The ornamental design for electric water gun, as shown and described.

DESCRIPTION

FIG. 1 is a top, front, and left perspective view of an electric water gun, showing my new design;

FIG. 2 is a bottom, rear, and right perspective view thereof;

FIG. 3 is a left elevational view thereof;

FIG. 4 is a right elevational view thereof;

FIG. 5 is a front elevational view thereof;

FIG. 6 is a rear elevational view thereof;

FIG. 7 is a top plan view thereof; and,

FIG. 8 is a bottom plan view thereof.

The broken lines depict portions of an electric water gun and form no part of the claimed design.

1 Claim, 8 Drawing Sheets
